UNITED STATES PATENT OFFICE.

GUSTAV PEETZ, OF NEW YORK, N. Y., ASSIGNOR, BY MESNE ASSIGNMENTS,
TO THOMAS J. MORAN, OF ARLINGTON, NEW JERSEY.

IRONING WAX-PAD.

No. 821,582.

Specification of Letters Patent.

Patented May 22, 1906.

Application filed August 24, 1903. Serial No. 170,507

To all whom it may concern:

Be it known that I, GUSTAV PEETZ, a citizen of the United States, residing in the borough of Manhattan, city, county, and State 5 of New York, have invented an Improvement in Ironing Wax-Pads, of which the following is a specification.

In carrying out my invention I employ a base and a backing upon which are superimposed and secured connected sheets of wax-saturated material. Over the connected sheets of wax-saturated material I preferably employ a sheet of paper and an outer layer of fabric, which latter parts are secured to the 15 base by a suitable binder.

In the drawings, Figure 1 is a plan of my improved ironing wax-pad; and Fig. 2 is a section, on a larger scale, at line *x* *x*, Fig. 1. Fig. 3 is a partial cross-section of a modification 20 of my improvement.

a represents a base of cardboard or other suitable material, and I have shown the same as rectangular; but it may be of any desired form.

25 *b* is a backing, preferably made of the same material as the base *a*, and corresponds to the same in outline, but is of smaller area. The backing *b* is secured to the base *a* by any means known to the art and in such a position that there is a border, equal on all sides, around the base.

30 *c d* are sheets of wax-saturated blotting-paper or other suitable material similarly treated, of the same size and shape as the backing *b*, and are secured together and to the backing *b* in any manner whatsoever. I also employ a sheet of Manila or other paper *e* and an outer layer of cheese-cloth or other open fabric *f*, and both the paper *e* and the 35 fabric *f* extend over the entire upper surface of the sheet *d* of wax-saturated material, over all the edges of both sheets *c d* of the wax-saturated material and the edges of the backing *b*, and over a portion of the surface 40 of the border of the base *a* and are secured in position by a binder *g*, which overlaps the edges of the paper *e* and fabric *f* and passes

over the edge of the base *a* and is secured to the under side thereof.

As shown in Fig. 3, I may employ a sheet 50 of waterproof paper *h* of the same area as the sheets of wax-saturated material *c* and placed between the same and the backing *b* in order to prevent the backing *b* and the base *a* from becoming saturated with wax. 55

The special object of this assembling and connecting the parts is to prevent the wax flowing and escaping under the heat of the iron when placed on top of the pad, as the melted wax retained within the closure is at 60 once taken up again by the blotting-paper or other similar suitable material upon the removal of the heated iron, and thus all of the wax with which the paper is charged is available for use without waste. 65

It is obvious that the sheet of paper *e* or the fabric *f*, or both, may be treated by an application of wax previous to making up the pads, so as to make more positive the dissemination of the wax from the sheets *c d* 70 in use.

I claim as my invention—

1. As a new article of manufacture, an ironing wax-pad, comprising a base, a backing, connected superimposed sheets of wax-saturated material, a sheet of paper over said sheet of wax-saturated material, a cover of open fabric, and a binder overlapping the edges of said paper and fabric, passing over the edges of the base and secured to the under side thereof. 75

2. As a new article of manufacture, an ironing wax-pad, comprising a base, a backing, connected superimposed sheets of wax-saturated material, a sheet of waterproof paper between the backing and the said wax-saturated material, a sheet of paper over said sheets of wax-saturated material, and a cover of open fabric. 85

3. As a new article of manufacture, an ironing wax-pad, comprising a base, a backing, connected superimposed sheets of wax-saturated material, a sheet of waterproof paper between the backing and the said wax- 90

2
saturated material, a sheet of paper over said sheets of wax-saturated material, a cover of open fabric, and a binder overlapping the edges of said paper and fabric, passing over the edges of the base and secured to the under side thereof.

4. As a new article of manufacture, an ironing wax-pad comprising a base, a backing, connected superimposed sheets of wax-

saturated material and a sheet of waterproof material between the backing and the superimposed sheets of wax-saturated material.

Signed by me this 21st day of August, 1903.

GUSTAV PEETZ.
